United States Patent Office

Des. 218,786
Patented Sept. 22, 1970

218,786

VTOL AIRCRAFT

Hans-Luzius Studer, Hamburg, Germany, assignor to
Hamburger Flugzeugbau GmbH

Filed Mar. 28, 1969, Ser. No. 16,496

Term of patent 14 years

Int. Cl. D12—07

U.S. Cl. D71—1

Des. 218,786

PAGE 2

FIG. 1 is a side elevational view of the VTOL aircraft;
 FIG. 2 is a front view of the design shown in FIG. 1;

FIG. 3 is a top view of the design shown in FIG. 1 with
 a fragment of the starboard wing omitted for ease of
 illustration;

FIG. 4 is a perspective view from underneath of the
 design shown in FIG. 1 in an attitude of vertical flight.

I claim:

The ornamental design for a VTOL aircraft, as shown
 and described.
